UNITED STATES PATENT OFFICE.

ANDREW S. HUNT, OF HOPE, ARKANSAS.

CHOCK.

Application filed September 24, 1926. Serial No. 137,612.

This invention relates to a chock designed for use on the bolster of a wagon or other vehicle and which, when in position, will prevent logs and similar articles from rolling off of the bolster on which they are mounted.

One of the objects of the invention is to provide simple and efficient means for attaching the chock to the bolster, said means being so constructed as to permit the chock to be removed readily when not in use.

A further object is to provide a chock which is simple, durable and efficient and can be easily applied.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is an end elevation of the chock, the bolster to which it is attached being shown in section.

Figure 2 is an elevation of one side of the chock and of the adjacent portion of the bolster supporting the same.

Figure 3 is a view similar to Figure 2 showing the other side of the chock and a portion of the bolster.

Referring to the figures by characters of reference 1 designates a block constituting the body portion of the chock, this block being formed with a beveled end 2 and being adapted to rest flat upon the top surface of a bolster B. The bolster is formed with a transverse key hole aperture C. Secured loosely to the sides of the block 1 are straps 3, these straps being held to the block by a bolt 4 extending transversely therethrough. One of the straps 3 is formed, near its lower end, with an aperture 5 preferably circular while the other strap 3 has a key hole slot 6 therein. Both of the apertures 5 and 6 are adapted to register with the ends of the opening C.

An attaching pin 7 is provided for holding the chock to the bolster. This pin has one

end reduced in diameter as shown at 8 and 55 offset to provide a radial lug 9. Extending from the other end of the pin is a crank arm 10.

When it is desired to apply the chock to a bolster, the same is placed in position thereon with the straps 3 extending along opposite sides of the bolster, as shown. The pin 7 is then arranged substantially vertically so that the end of the lug 9 can be inserted into the opening 5 whereupon the pin is 60 swung through an angle and slid longitudinally of the aperture C. The lug 9 may pass through the slot 6 after being turned into alignment therewith subsequent to emerging from the slot C and then, by turning the 65 crank arm 10, the lug will turn downwardly to the position shown in Figures 1 and 3, thereby preventing the pin from being withdrawn from engagement with the parts.

It will be apparent that when the parts 70 are assembled as described the chock will be held securely to the bolster and when this chock is arranged with its beveled or inclined end innermost, it will constitute a rest or abutment for logs or the like supported 75 by the bolster. The pressure of the logs will tend to thrust the chock outwardly but this outward movement will be limited by the straps 3 with the result that the parts will be bound tightly together and cannot 80 slip.

For the purpose of removing the chock from the bolster the crank 10 is provided so that the pin 7 can be rotated to swing the lug 9 upwardly. The pin is then withdrawn 85 from engagement with the slotted strap 3 after which it is swung downwardly to permit withdrawal of the lug from the opening 90 5. As the crank 10 normally hangs downwardly, it tends normally to hold the parts 95 securely fastened together so that they will not become accidentally disconnected.

What is claimed is:

The combination with a bolster having a slot extending therethrough, of a chock including a block, straps pivotally connected to the sides of the block and extending through the side of the bolster, there being an aperture in one of the straps adapted to register with a portion of the chock in the bolster and a slot in the other strap adapted to register with a portion of the slot in the bolster, a pin having an offset lug extending 100 105

radially from one end portion thereof, said same to said position, said arm constituting lug being insertable through the aperture in one of the straps, rotatable to position for insertion through the slot in the bolster, and then rotatable to position for insertion through the slot in the other strap, and an arm extending from the pin for rotating the

means for holding the lug normally out of alignment with the slot in the strap. In testimony that I claim the foregoing as my own, I have hereto affixed my signature.

10

ANDREW S. HUNT.
